FREDERIC NEWTON GISBORNE AND HERBERT ALLMAN, OF LONDON,
ENGLAND.

Letters Patent No. 79,823, dated July 14, 1868.

IMPROVEMENT IN LAMP-OHIMNEY ATTACHMENTS.

The Schedule referred to in these Letters Patent and making part of the same.

TO ALL WHOM IT MAY CONCERN:

Be it known that we, FREDERIC NEWTON GISBORNE and HERBERT ALLMAN, British subjects, and residents of the city of London, England, have invented a "Thermodynamic Gas-Valve;" and we do hereby declare that the following is a full, clear, and exact description thereof, reference being had to the accompanying drawings, making a part of this specification, and to the letters of reference marked thereon, in which—

Figure 1 is a transverse section of the valve.

Figure 2 is a plan view of the same.

Figure 3 is a perspective view of the valve; and

Figure 4 is a view of a glass chimney, with valve attached.

The nature of our invention consists in the regulation of the current of atmospheric air admitted to the flame produced by the ignition of coal or other carburetted gases in lamps or burners; said regulation being accomplished by means of the movement of a valve, so placed as to open or close the air-passage. This movement of said valve is produced by the action of the heat of the flame upon a compound bar attached to the ring or some portion of the valve.

That others skilled in the art may be able to make and use our invention, we will proceed to describe its construction and mode of operation.

In the drawings, *a* represents a circular frame, ring, or gallery, having a circular hole therein; and upon one side of said ring, and near the hole, is attached the disk *c* by means of the hinge *b*. Upon the opposite side of the hole is attached the bar *d*, secured in any proper manner. We prefer a screw, as we can then change the adjustment of the bar at pleasure, said bar projecting out over, or partially across, the hole in the ring, and underneath the disk *c*.

This bar *d* may be termed a compound bar, as it is composed of two metals of different expansibility, as steel and brass, and said compound bar is attached to the ring *a*, with the brass portion underneath, or nearest the flame.

The two pieces of metal of which the bar is composed are firmly secured together by riveting or soldering. To any part of the ring *a* is secured the rod *h*, which is so bent that its lower end shall be nearly under the centre of the hole in the ring, and a short distance below it, say one inch; and to the lower end of said rod *h* is attached the disk *F*, or the rod *h* may be bent in any way so that the said disk *F* may be suspended nearly under the centre of the ring, or under the disk or valve *c*.

For convenience in handling or using, we make an ornamented coronet, *a'* *a'*, having a gallery upon the inside, and into this coronet *a'*, and upon said gallery, we place the ring *a*, and then place the coronet containing the valve into the top of the chimney or globe of the lamp or burner, the coronet *a'* resting upon the top of the chimney, as shown in fig. 4. This coronet, however, we do not confine ourselves to the use of, as the valve is equally as operative without as with said coronet, it being more for convenience and ornamentation, than otherwise; and in practice, if the coronet is used, the button or disk *F* is equally as operative if the rod *h* is attached to said coronet instead of being attached to the ring *a*, though we prefer to attach it to the latter.

The valve or disk *c* may have a small hole therein, if desirable, and a small piece of metal may be attached to the ring underneath the disk *c*, and near the hinge, said piece of metal serving as a prop to keep the valve open a little before the heat acts upon the compound bar, as it prevents the gas from smoking when first lighted.

We will now proceed to describe the operation of the valve.

If said valve be placed upon the top of a chimney or globe of a lamp or burner, the heat of the flame expands the metals of which the bar *d* is composed, and the brass upon the lower side of said bar being of greater expansibility than the iron or steel, the greater expansion of said brass portion causes the whole bar *d* to bend or curve upward, thereby lifting the valve or disk *c*, which rests upon it.

It is evident that the opening or closing of the valve-plate *c*, by the action of the bar *d*, regulates the

amount of air passing through the glass or chimney. Thus, when the flame is not ignited the valve is nearly closed; but on the ignition of the gas and appearance of the flame, the bar *d*, under the influence of the increasing temperature below, begins to open the valve, as described, by bending the compound bar upward. As the flame and temperature is augmented, the valve opens, giving a larger equivalent of atmospheric air or oxygen, thus producing a more perfect combustion of the carburetted gases.

The button *F*, attached to the lower end of the rod *h*, serves to check the draught slightly, or to deflect the current of air in its upward passage out of the chimney, and cause it to spread laterally before passing out through the opening. By this means the flame is caused to burn more steadily, avoiding any tendency to "flicker."

It is evident that the several parts of the valve may be constructed of various materials capable of resisting the action of fire, such as iron, brass, china, earthenware, mica, or other suitable materials; and the valve may be used for the more perfect combustion of coal or other carburetted gas, or gas generated by the combustion of paraffine-oil, or any other liquid ordinarily used for lighting purposes.

This valve may be varied in form, and we do not, therefore, wish to be confined to this particular form or shape of valve; neither do we wish to limit ourselves to the use of any two particular metals in the construction of the bar *d*, as any two metals of different expansibility will be equally operative, provided they are not fusible at the heat they would be subjected to for the above purposes.

By our invention we are enabled to increase the illuminating power of the flame about one hundred per cent. without any increased consumption of the gas, and at the same time we obtain a purer flame, and this without any care or trouble, as the apparatus is self-adjusting. We prefer, however, to use the valve as described, as accomplishing the best results.

Having thus described our invention, what we claim as new, and desire to secure by Letters Patent, is—

1. Our improved apparatus for regulating the supply of air to the flame of a lamp or burner, when constructed and arranged substantially as herein described and set forth.
2. The combination of a disk or button, *F*, with an opening or valve placed above it, substantially as described and herein set forth.
3. The combination of the compound bar *d*, the hinged valve *c*, and perforated rim *a*, the whole used in connection with a lamp or gas-chimney, substantially as herein described, and for the purposes specified.

LONDON, November 14, 1867.

FREDERIC NEWTON GISBORNE,
HERBERT ALLMAN.
